UNITED STATES PATENT OFFICE

HAROLD A. RINGEL, OF NEW ORLEANS, LOUISIANA, ASSIGNOR TO ELMER CANDY COMPANY, INC., OF NEW ORLEANS, LOUISIANA, A CORPORATION OF LOUISIANA

DESIGN FOR A BASKET

Application filed April 23, 1930. Serial No. 35,355. Term of patent 7 years.

To all whom it may concern:

Be it known that I, HAROLD A. RINGEL, a citizen of the United States, residing at New Orleans, in the parish of Orleans and State of Louisiana, have invented a new, original, and ornamental Design for Basket, as shown in the accompanying drawing and described in the following specification.

In the accompanying drawing, Figure 1 is a perspective view of a basket showing my design.

I claim:

The ornamental design for a basket as shown.

HAROLD A. RINGEL.
